TRIES, OF TORRIDON, LEEDS, ENGLAND

RING-SPINNING FRAME FOR WOOLENS

Application filed November 19, 1928, Serial No. 320,459, and in Great Britain February 27, 1928.

This invention relates to ring spinning frames for wool and also cotton and other fibres, the chief object being to control the thread during drafting with a view to the 5 production of a more uniform yarn at a higher draft than usual.

According to the invention, means are provided in place of the usual deflection rod whereby the tension of the thread controls 10 its mode of entrance to a false twist tube which leads the thread into the nip of the drawing rollers. The mouth of the false twist tube may be countersunk or flared and have a plurality of notches or projections 15 in or on its conical or flared face, while the thread may first pass over a tension "controller" which may consist of a revolving roller or some such equivalent device, together with a smooth floating roller, the 20 downward pressure upon which is counterbalanced in any appropriate manner.

In order that the invention may be clearly understood and readily carried into effect, the same will now be more fully described 25 with reference to and by the aid of the accompanying drawings; wherein:—

Figure 1 is a side elevation of a false twist tube and means whereby the tension of the thread controls its mode of entrance thereto.

Figure 2 is a plan view of the false twist tube drawn to an enlarged scale.

Referring to the drawings, the thread 1 first passes over a tension "controller" which, in the embodiment shown, consists of 35 a revolving roller 2 together with a smooth floating roller 3 the downward pressure upon which is counterbalanced. Thus the floating roller 3, which may be made of glass, metal or other appropriate material, is mounted at 40 one end of a double-ended lever 4 freely pivoted at 5, the other end of said lever 4 having slidably mounted thereon a balance weight 6. By adjusting the position of the balance weight 6 along the arm of 45 the double-ended lever 4 the tension of the thread 1 is adjusted, and in this way the angle or mode of entrance of thread 1 into the mouth piece 7 of the false twisting tube 8 is controlled. As shown, the thread 1 50 is just clear of the roller 2 when working

normally, said roller 2 serving to prevent the angle of entrance of the thread 1 into the mouth piece 7 from becoming too acute. The mouth piece 7 of the false twist tube 8 is in the form of a countersunk or flared head having a plurality of spaced pins 9 passed at an angle therethrough to afford a plurality of projections on the conical or flared surface of the mouth piece 7, said projections serving to positively engage the 55 thread 1 and impart twist thereto during the revolutions of the false twist tube 8. The bore of the false twist tube 8 may be smooth, rough or rifled and is restricted at its lower end, while spring jaws 10 or equivalent 60 means may be provided on the lower end of the twist tube 8 so as to grip the thread 1 in its passage into the nip of the drawing rollers 11, and in this connection the spring jaws 10 are so shaped that they may be 65 brought as close to the nip of said rollers 11 as possible. The false twist tube 8 is revolvably mounted in a bearing bracket 12 secured to a cross member 13 of the machine frame, and said twist tube 8 is adapted to 70 be driven by means of a pulley 14 secured thereto by a set screw 15, although it will be understood that any other appropriate means may be employed for driving the false twist tube 8. The mouthpiece 7 is secured 75 in position within the upper end of the false twist tube 8 by means of a set screw 16, while a set screw 17 serves to secure the balance weight 6 in any adjusted position on the arm of the double-ended lever 4. 80

What we claim as our invention is:—

1. In combination with a spinning machine of the class described, a twist tube having at one end a flared mouth provided with oppositely disposed inclined radial projections arranged to engage the thread and impart a twist thereto upon actuation of the tube, depending resilient fingers connected to the opposite end of the twist tube for applying a uniform pressure on the thread as it issues from the tube, a lever 90 associated with said twist tube, said lever having a smooth floating roller for engaging the thread, and a revolving roller positioned 95 in front of said floating roller for control- 100

ling the angle at which the thread enters into the twist tube.

2. In combination with a spinning machine of the class described, a twist tube having at one end a flared mouth provided with oppositely disposed inclined radial projections arranged to engage the thread and impart a twist thereto upon actuation of the tube, depending resilient fingers connected to the opposite end of the twist tube for applying a uniform pressure on the thread as it issues from the tube, a lever associated with said twist tube, said lever having a smooth floating roller for engaging the thread, adjustable means for counterbalancing the downward pressure of said roller, and a revolving roller positioned in front of said floating roller for controlling the angular entrance of the thread into the twist tube, said revolving roller arranged to be normally out of engagement with the thread.

3. In combination with a spinning machine of the class described, a twist tube having at one end a flared mouth provided with oppositely disposed inclined radial projections arranged to engage a thread and impart a twist thereto upon actuation of the tube, the opposite end of the twist tube having a reduced axial extended portion, drawing rollers below said reduced portion, depending spring fingers connected to said tube and extending close to said drawing rollers so as to exert a uniform pressure on the thread as it passes to the nip of the drawing rollers, a lever associated with said twist tube, said lever having a smooth floating roller for engaging the thread, and a revolving roller positioned in front of said floating roller for controlling the angular entrance of the thread as it enters the twist tube.

4. A twist tube for spinning machines having at one end a mouth provided with inwardly inclined projections for engaging the thread, and spring fingers connected to the opposite end of the twist tube for applying a uniform pressure on the thread as it issues from the tube.

5. A twist tube for spinning machines having at one end a mouth provided with inwardly inclined projections for engaging the thread, and a reduced axial extending portion at its opposite end, and resilient means extending axially from the reduced portion of the twist tube for applying a uniform pressure on the thread as it issues from the tube.
